ISAAC W. FORBES, OF LA PORTE, INDIANA.

Letters Patent No. 98,753, dated January 11, 1870; antedated December 14, 1869.

IMPROVED OSCILLATING STEAM-VALVE.

The Schedule referred to in these Letters Patent and making part of the same.

To all whom it may concern:

Be it known that I, ISAAC W. FORBES, of La Porte, in the county of La Porte, and State of Indiana, have invented new and useful Improvements in Oscillating Valves; and I do hereby declare the following to be a clear and exact description thereof, sufficient to enable others skilled in the art to which my invention appertains, to fully understand and use the same, reference being had to the accompanying drawings, making a part of this specification, in which—

Figure 1 is an elevation of the device illustrating my invention.

Figure 2 is a central vertical section thereof.

Figure 3 is a top or plan view thereof.

Figure 4 is a plan view of the valve-seat.

Figure 5 is a bottom view of the valve.

Figure 6 is a top view of the balance-head of valve on a smaller scale.

Figure 7 is a central vertical section of fig. 6.

Figure 8 is a central vertical section of the valve without the balance-head.

Figure 9 is a bottom view of the valve.

Figure 10 is a central vertical section of the valve and balance-head connected with the valve.

Figure 11 is a plan view of fig. 10.

Figures 12 to 21, inclusive, are modifications, and the parts constituting them being partly in sectional and partly in top and bottom views.

Similar letters of reference indicate corresponding parts in the several figures.

My invention consists in the construction, as hereinafter made known, of oscillating valves, whereby they are nearly balanced, and thus require but little power to move them, as will be hereinafter more fully described.

In the drawings—

A represents the spindle or axis of the valve, which may be made of wrought-iron or steel, passing through the valve-case E, working in a centre or step on the valve-seat.

B is an arm, which is keyed to said axis, and properly held thereon by a nut, C, or other fastening. This arm may be connected to the working parts of the engine, or to the power which produces valve-motion. Instead of this arm, gearing may be employed.

D represents the stuffing-box, the object of which is to assist as a bearing for the valve-stem, and to prevent the leakage of steam which might otherwise take place.

The valve-case E has a flange, G, at the lower end, by which it is bolted to the face of the cylinder, and a boss on one side to receive the steam-pipe F, by means of which steam is admitted into the case.

H is the flange of the valve-seat or cylinder-face, and I I are nuts and studs, for fastening the valve-case to the cylinder.

K represents the head of the valve. It may be a portion of the lower part of the valve, and shrunk solid thereon, or placed loosely thereon, in which case its upper portion will rest against a collar, L, on the spindle.

The periphery of the head has a steam-packing ring, K', which fits the case, bored out and finished, for the purpose of preventing the steam from passing to the upper surface, or a series of grooves may be employed in place of said ring, if the balance-head is small, in which case the groove should be in the head, and corresponding ones are in the case, and might be used for any-size valve instead of said ring, which some might prefer. If the head is solid, as in fig. 10, the ring will be necessary.

M represents the hull or shell forming the outer wall of the exhaust-chamber P.

M¹, the top or cover of port.

M², the rim, extending around the outer portion of the recess Z, through which the steam passes, for equalizing downward pressure; but this rim may be dispensed with, if desired.

P is the exhaust-chamber, which corresponds in area with the area of the exhaust-port O, in addition to the divisions T, between the exhaust-port O and receiving-ports S.

Recesses Q Q are formed in the flanges of valve-case and valve-seat, to prevent leakage.

A series of grooves, a a, is formed in the spindle, balance-head, and the collar L, corresponding to each other, and intended to prevent the passage of steam to the upper portion of the balance-head, between the balance-head and spindle.

Should water accumulate above the balance-head, it will be conveyed, through the openings R R in the valve-stem, to the exhaust-port P, when used as a main valve.

The operation is as follows:

The upper head of the valve fits the inside of the case with steam-packing ring, or otherwise, for the purpose of preventing steam from passing. Steam is introduced into the case through pipe F, and between the head and lower part of the valve. By these means the valve is nearly balanced, the upper head being smaller than the lower portion, and able thus to produce a downward pressure sufficient to hold it on the valve-seat.

As the valve is oscillating, the ports are opened by means of a recess, Z, corresponding with the ports. Steam is received in the port over which the recess Z happens to be. The recess should not be moved further than to give a full port. In fact it need not be moved more than two-thirds of a port. When the valve is moved back, the port S is closed, and the exhaust-chamber P, passing over the division T between the exhaust-port O and receiver-port S, so as to allow

steam to exhaust at the proper time, then the recess Z passes over the opposite receiver-port S, which in turn receives the steam, this port S being again closed by the return motion of the valve.

The exhaust-port may extend entirely through the valve, above the balance-head, to prevent the steam from raising the valve as it exhausts. In case that it may be desired or required, the exhaust may pass through the valve and out at the upper portion of the valve-case; or it may pass to the case above the head, and exhaust through the valve-seat, as represented in modifications, when the channel R will not be required. But if the balance-head and lower port are made of one piece, then it will be necessary to make the space between the head and the lower portion larger, in order to allow a free passage for steam to the upper portion of the head; or, if necessary, the valve-stem may be larger and the head be loose, and the channel R made large and used for that purpose. In this case, the balance-head will have to be made as great in area as will compensate for the lift produced by the exhaust steam.

The lapse of the valve and the size of ports may be of any dimensions consistent with the size of the same.

The above description relates to valves having seats with two induction-ports and one exhaust-port, but there may be four induction-ports and no exhaust-port through the valve-seat.

Fig. 17 represents valve-seat when this modification is applied, where valves are used upon locomotives, which are liable to have the exhaust-pressure varied to suit the different grades and blasts to prevent them from rising from their face when there is a heavy exhaust-pressure upward.

In place of the exhaust P extending through the valve to the upper surface of the balance-head, for the purpose of equalizing pressure, a cap or bail may extend from the case to the upper portion of the valve-spindle, with a set-screw through the same to press upon the centre of the spindle and prevent the valve from rising.

Two opposite ports, b b, must lead to one end of the cylinder, whilst the other two, c c, lead to the opposite, and the valve will require but one-half the motion to produce the openings that were produced when only two induction-ports were used. In this case, the valve has two openings, d d, one each side of the centre, corresponding to the ports in the valve-seat. Each receives steam, and each passage is of the same area as the ports in the valve-seat, through which steam passes into the ports.

There are two openings, e e, through the valve, quartering with the steam-passages d d, each having twice the area of one induction-port. (See fig. 15.) These openings pass entirely through the valve for exhausting steam, through the top of the valve-case, and through the exhausting-pipe U. In this case, steam is admitted in the valve-case to the valve through the induction-pipe U.

To illustrate this more fully, the valve-seat, at its circumference, is spaced off into twenty-four equal parts, with lines drawn from the centre to the points

marked off. Two of the spaces between the lines, at opposite points from the centre, are taken out at each quarter, leaving sufficient area at the centre to support the valve, and a rim at the circumference. There will be left in the valve-seat, between each port, a surface twice the area of the port. The bottom part of the valve is to be marked off in the same manner as the valve-seat, *i. e.*, into twenty-four parts.

Two openings are made at opposite points to each other, each one comprising two of the spaces through which steam passes into the ports.

On each side of the openings are left surfaces, f f, comprising three spaces each, and the four remaining spaces e e upon opposite points are cored out through the valve for the exhaust steam to pass when there are four induction-ports. But half the motion of the valve is necessary to produce the same area in the opening that is required with but two induction-ports.

The valve-seat, fitting inside the valve-case, is raised about one-eighth of an inch, or the valve-seat may be conical, or steam may be received through the top of the valve and passed through the same, through the ports of the engine, and exhaust below the head through the valve-case, as seen in figs. 16 and 18, in which case the steam passes into the pipe V, through the top of the valve, and through the small recesses e' into the engine-ports, and exhausting through valve, through spaces e', and the exhaust-pipe below the head.

Fig. 13 is a top view of the valve in figs. 12 and 15.

Fig. 14 is a top view of the valve in figs. 16 and 18.

The principle of my invention is applicable to throttle-valves, which, as is well known, require no exhaust-port, as represented in fig. 19, which is a central vertical section. The modifications in figs. 12 to 21, inclusive, may revolve, if required.

Steam is received in the steam-pipe, and passes through the lower portion of the valve through the openings e', and through openings e' in the valve-seat, the openings in the valve and in the valve-seat being of the same area and shape, and corresponding to each other; f f', covering the steam-passage in the valve-seat, as the valve is closed, the lower portion being keyed, or may be shrunk upon the valve-spindle.

An opening, g, is formed in the valve-case, above the balance-head, to allow the escape or exit of condensed steam.

Having thus described my invention,

What I claim as new, and desire to secure by Letters Patent, is—

1. The oscillating valve, constructed substantially as herein described.

2. The balance-head K, applied and operating substantially as described.

To the above I have signed my name, this 27th day of August, 1869.

I. W. FORBES.
